UNITED STATES PATENT OFFICE.

THOMAS W. KINGS, OF CHICAGO, ILLINOIS, ASSIGNOR TO IRA E. BURTIS, OF CHICAGO, ILLINOIS.

MOTOR.

1,119,758.

Specification of Letters Patent.

Patented Dec. 1, 1914.

Application filed November 27, 1912. Serial No. 733,858.

To all whom it may concern:

Be it known that I, THOMAS W. KINGS, a subject of the King of Great Britain, residing in Chicago, county of Cook, and 5 State of Illinois, have invented certain new and useful Improvements in Motors, of which the following is a specification.

The present invention relates to motors generally and more particularly to motors 10 in which a fluid, such as compressed air, is used to reciprocate one or more pistons.

The principal object of the invention is to provide a motor which shall be simple in construction and efficient in operation.

15 An important feature of my invention consists in a novel control valve by which the fluid is controlled in its passage to the pistons. This valve consists of a simple reed rigidly secured at one point and operating between opposed ports at another point, the reed lying normally out of contact with said ports.

Another important feature of my invention 20 consists in a novel arrangement of pistons by which the motor is enabled to start in any position of its movable parts.

Other features of invention reside in the arrangement and details of the parts.

These several features will be best understood upon reference to the following detailed description taken in connection with the accompanying drawing, and the scope 25 of the invention will be particularly pointed out in the appended claims.

30 In the drawing, Figure 1, is a transverse vertical section of a motor constructed in accordance with my invention, the plane of section being indicated by the line 1—1 of Fig. 2; Fig. 2 is a vertical elevation of one-half of the motor, a portion being shown 35 in section taken on plane indicated by the line 2—2 of Fig. 1; Fig. 3 is a transverse section of the motor taken on a plane indicated by the line 3—3 of Figs. 1 and 2; and Fig. 4 is a longitudinal section of a modified 40 piston arrangement.

Throughout these views like characters refer to like parts.

Referring to the drawing in detail, 45 10 and 11 indicate opposed cylinders; 12 and 13, cup-shaped pistons in said cylinders; 14, a base for supporting said cylinders; 15, a rock-shaft journaled in said base; 16, a rock-arm secured to, or preferably formed integral with, said arm and terminating at

its upper end in a spacer 17, which lies between the adjacent faces of the pistons 12 and 13 and maintains them a proper distance apart for all positions of the mechanism. As shown, the base 14 and the 60 cylinders 10 and 11 are preferably formed in two castings which are adapted to be held together by suitable bolts 18 and 19. Cylinder 10 is provided with an inlet port 20 and an exhaust, or outlet, port 21. Cylinder 11 is provided with similar ports 22 and 23. The two castings which make up the cylinders 10 and 11 and the base 14, when assembled, are provided with a threaded boss 24 for the engagement of a tubular coupling 65 25 which is threaded at its outer end for the reception of a supply pipe 26. Extending from that portion of the boss 24 which is formed on one of the castings is a shank 27. A recess 28 is also formed in the opposing 70 faces of the castings adjacent to the shank 27. A reed 29 is secured at its outer end to the outer end of the shank 27 by a plate 30 and screws 31 extending through the plate and the reed into the shank. The free end of the reed 29 extends into the recess 28. Ports 32 and 33 open out of the recess and are positioned opposite to each other so that the free end of the reed 29 may alternately 75 engage them and close them. The valve 80 port 32 communicates with the cylinder inlet port 20 by passage 34; and the valve port 33 similarly communicates with inlet port 22 by a passage 35.

In operation the fluid, which is preferably compressed air, is admitted through the supply pipe 26 into the chamber formed within the coupling 25. Normally, the reed 29 lies midway between the ports 32 and 33. With the pistons in the position 85 90 shown, upon such admission of the actuating fluid, a certain portion of it will flow through passage 35 into cylinder 11 and out through its exhaust port 23. At the same time air will flow through passage 24 into cylinder 10. This will produce unequal pressures on opposite sides of the reed valve 28 and the latter will close port 33. The pressure of the fluid in cylinder 10 will cause piston 12 to press against spacer 17 and the latter will in turn press against piston 13 to force it to close its exhaust port 23 and to compress the entrapped air in cylinder 11 and passage 35. This action 95 100 will cushion the piston 13 against the end 105 110

of the cylinder 11. This movement of these parts will rock the shaft 15 in one direction. As soon as piston 12 advances far enough to open its outlet port 21, the pressure in cylinder 10 and in passage 34 will be immediately reduced, and the reed 29 will close port 32 and immediately the actuating fluid will be admitted to cylinder 11 to drive the parts in the opposite direction. 10. This will return the shaft 15 to the first position. This action will be constantly repeated and the pistons 12 and 13 reciprocated back and forth with the resulting oscillation of the rock-shaft 15. This shaft 15 may be connected to any suitable mechanism to which it is desired to give a to-and-fro movement, such as a sand-sifter or similar device.

In the modification illustrated in Fig. 4, 20 the pistons 12" and 13' are the same as the pistons 12 and 13 in Fig. 1, but the spacer 17' is formed integral with them instead of integral with the arm 16, as in Fig. 1. The arm 16' in this modification is bifurcated at 25 its upper end so as to straddle the spacing-shank 17' to receive its proper oscillating movement upon the reciprocation of the pistons.

I have found in practice that when the 30 pistons are made up in the form illustrated in Figs. 1, 2 and 3, with the spacer 17 separate from the pistons, the motor will start up upon the admission of the actuating fluid through the supply pipe 26 no matter 35 what position the motor may have stopped in. I have found, on the other hand, that when the pistons are assembled as illustrated in Fig. 4, the shaft 15 must be rocked so as to bring the arm 16' into one extreme 40 position or the other before it is possible to start the motor. I am unable, at the present time, to explain this difference in operation, but have demonstrated it to be the fact.

45 In carrying out my invention it will be apparent that certain alterations and modifications may be made in the details and arrangements of the parts without departing from the spirit and scope of my invention. 50 I, therefore, do not wish to be limited to the specific embodiments of my invention herein

disclosed, but aim to cover all such alterations and modifications by the terms of the appended claims. And I wish it understood that I may use steam or other fluids as well as compressed air to operate my motor. 55

What I claim as new and desire to secure by Letters Patent of the United States is:

1. A motor comprising two oppositely disposed cylinders, pistons in said cylinders, a spacer between said pistons, said spacer and each of said pistons constituting structurally independent units operatively movable relative to one another, inlet ports at the outer ends of said cylinders, outlet ports inward of said inlet ports, control valve ports communicating with said inlet ports and positioned opposite each other, a reed rigidly secured at one point and operating at a free point upon said valve ports to alternately open and close them, said reed lying normally out of engagement with said ports, and a chamber inclosing said reed and having suitable fluid supply connections. 65

2. A motor comprising two oppositely disposed cylinders, pistons in said cylinders, a spacer between said pistons, said spacer and each of said pistons constituting structurally independent units operatively movable relative to one another, inlet ports at the outer ends of said cylinders, outlet ports inward of said inlet ports, control valve ports communicating with said inlet ports and positioned opposite each other, a reed rigidly secured at one point and operating at a free point between said valve ports to alternately open and close them, said reed lying normally out of engagement with said ports, a chamber inclosing said reed and having suitable fluid supply connections, a frame 80 for supporting said cylinders, a rock shaft journaled in said frame, and an arm secured at one point to said rock shaft and connected at another point to said spacer. 85

In witness whereof, I hereunto subscribe 90 my name this 23rd day of November, A. D., 1912.

THOMAS W. KINGS.
